UNITED STATES PATENT OFFICE.

FRANK J. SKONIER, OF ALTOONA, PENNSYLVANIA.

AIR-CONTROL VALVE.

Application filed March 18, 1927. Serial No. 176,569.

The invention relates to a novel construction of valve device adapted to control the circulation or supply or the circulation and supply of the air in refrigerating, drying or similar apparatus, the successful operation of which requires various changes in the pneumatic conditions within the refrigerating, drying or similar chamber or receptacle. The invention is illustrated in the accompanying drawings, in which:

Fig. 1 illustrates the apparatus as applied to a typical refrigerating or drying system.

Fig. 2 is an enlarged sectional elevation of the valve device.

Fig. 3 is a cross section on line 3—3 of Fig. 2.

Fig. 4 is an inverted perspective of the valve device.

Referring to the drawings, 10 indicates the casing of the valve, preferably consisting of sheet metal sections, welded, soldered or otherwise connected together to form a generally Y-shaped structure having an air pressure inlet 11 at one end, an atmospheric inlet 12 at the opposite end, a supply outlet 13 disposed laterally of inlet 12 and an exhaust outlet 14 similarly disposed on the opposite side of inlet 12, the cross section of the elements of the casing constituting the two inlets and outlets preferably being rectangular, whereby the construction of the casing is facilitated and the installation and operation of the cooperating butterfly valve member 16 is simplified and assured.

Said butterfly valve member comprises a flat plate of metal provided with a pivotal shaft or pintle 15 intermediate its ends and journaled in the opposite walls of the casing 10 and provided with an exterior operating handle 17, which is preferably disposed in substantial parallelism with the plane of valve 16 and thereby indicating the various positions of the valve with relation to the several passageways of the casing. The upper edge of the valve is adapted to engage the inclined side walls of the valve casing, when the valve is moved to either of its extreme positions, as shown in full and dotted lines in Fig. 2. The lower end of the valve is adapted to engage a stop plate 19 secured to the inner wall of the casing adjacent the supply outlet opening 13.

Connected to the inner wall of the exhaust outlet is a plate 18, which is also secured to the front and back walls of the

casing 10 with its upper edge in contact with the shaft or pintle 15 of the valve 16, so that, when the valve is moved to one extreme position, as indicated in full lines 60 in Fig. 2, the lower part of the valve engages plate 18; the primary object of this supplemental plate 18 is to form a wall of the passageway connecting the air pressure inlet section and the exhaust outlet section 65 of the valve and to bring about the proper functioning of the valve mechanism, when the latter is employed to effect combined circulation and supply of air, as will be 70 hereinafter explained.

A typical application of the invention is illustrated in Fig. 1, in which 1 indicates a chamber or compartment of a cooling, refrigerating or drying system in which the atmospheric conditions must be varied from 75 time to time to effect the best results, as, for example, a continuous exhaust of air from the chamber 1 and a concurrent supply of atmospheric air to said chamber, or a continuous circulation of air through the 80 chamber, or an accurately regulated combination of the two operations, to wit, a partial exhaustion of the air from the chamber, the complementary supply of atmospheric air and a simultaneous, continuous 85 circulation of part of the air in the compartment 1. To effect these results with certainty and accuracy, the chamber 1 is provided with the typical arrangement of exhaust pipes 2 near the ceiling, which open 90 into an exterior pipe 3, which is connected to the intake side of an exhaust fan or equivalent apparatus 4, the exhaust end of which is connected to the air pressure inlet 11 of the valve mechanism. A supply pipe 95 20 connected to the supply outlet 13 of the valve mechanism is connected to the lower part of the chamber 1. As a matter of convenience and sanitary precaution, an atmospheric inlet pipe 21 is connected to the inlet 100 12 of the valve and extends outside of the building, preferably above the roof; similarly and for the same reasons an exhaust pipe 22 is connected to exhaust outlet 14 105 of the valve and is extended above the roof of the building. The operation of the apparatus is as follows: When the valve 16 is adjusted to the position shown in Figs. 1 and 2, the exhaust fan 4 withdraws the air from the chamber 1 and forces the same 110 through the controlling valve mechanism out of the exhaust port 14 thereof to the

atmosphere through the exhaust pipe 22. This produces a reduction of the atmospheric pressure in chamber 1, which is compensated for by fresh air flowing by way 5 of pipe 21 and atmospheric inlet 12 of the valve, thence through the supply outlet 13 of the valve and pipe 20 into the chamber 1. Under some circumstances, it is desirable to effect a continuous circulation of the 10 same body of air through the chamber 1 and this is effected by shifting the valve 16 to its opposite extreme position, as indicated in the inclined dotted lines in Fig. 2, in which the upper edge of the valve 16 engages the inclined wall of the valve casing and the lower end of the valve engages the abutment plate 9. This cuts off communication with the exhaust port 14 and the atmospheric air inlet 12 and establishes direct communication between the air pressure inlet 11 and the supply outlet 13, so that the air withdrawn from the chamber 1 by the fan blower 4 is forced back into the chamber 1 by way of supply outlet 13 and 20 pipe 20. Under certain conditions of operation, it is found desirable and necessary to effect a continuous circulation of part of the air in chamber 1 and a simultaneous exhaust of part of the air from said chamber with a concurrent supply of fresh atmospheric air to the chamber and the balance between the circulated air and the fresh air supply must be effected with extreme accuracy to produce the best results. 30

These conditions are brought about by adjusting the valve 16 to an intermediate position, as indicated by the vertical dotted lines in Fig. 2, in which the valve occupies an intermediate position although it is obvious that it may be adjusted to any desired intermediate position between the extremes, thereby regulating the necessary balance between the circulating air and the partial exhaust and compensating supply of fresh 40 air. When the valve has been adjusted to any such intermediate position, the fan blower 4 withdrawing the air from chamber 1 forces a part of the same through the valve out of the exhaust opening 14, the portion of air so exhausted being determined by the relative position of the valve 16, the remaining portion of the air being directed past the upper edge of the valve 16 through the supply outlet 13 and pipe 20 back into chamber 1, thereby effecting a continuous circulation of this portion of the air. As the amount of air in circulation is not sufficient to maintain the normal pressure in chamber 1, the deficit is supplied by air entering by way of pipe 21 and air inlet 12 past the lower end of valve 16, thence by supply outlet 13 and pipe 20 into the chamber 1. Under these conditions of op-

eration, the baffle plate 18 is effective in preventing substantially all of the air being forced through the valve by blower 4 and then through exhaust outlet and the atmospheric inlet 12, which, of course, would destroy the desired balance between the circulating air and the partial exhaust of used air and the compensated supply of fresh air. 65

What I claim is:

1. An air control valve device comprising a casing having an air pressure inlet at 75 one end, an atmospheric air inlet and supply and exhaust outlets at the other end, said exhaust outlet having an inner wall extending within the casing, and a plate valve pivoted within the casing at the end of said wall and adapted to connect the air pressure inlet with the exhaust outlet and the atmospheric air inlet with the supply outlet or to connect the air pressure inlet with the supply outlet in the respective extreme positions of the valve, and to effect the several stated connections simultaneously when the valve is in intermediate position. 80

2. An air control valve device comprising 90 a casing having oppositely disposed air pressure and atmospheric air inlets, supply and exhaust outlets disposed laterally of and adjacent the atmospheric air inlet, a centrally pivoted butterfly valve in the casing 95 adapted in one extreme position to establish connection between the air pressure inlet and the exhaust outlet and between the atmospheric air inlet and the supply outlet and in its other extreme position to establish connection between the air pressure inlet and the supply outlet, and a baffle plate extending from one wall of the exhaust outlet to the axis of the valve, whereby when the valve is in intermediate position the several stated connections will be simultaneously established. 100

3. An air control valve device comprising a casing having an air pressure inlet and an atmospheric air inlet at opposite ends 110 thereof, laterally disposed supply and exhaust outlets, a valve plate pivoted intermediate its ends within the casing adapted to connect the air pressure inlet and exhaust outlet and the atmospheric air inlet and supply outlet in one position, and to close the exhaust outlet and connect the air pressure inlet and supply outlet in another position, and a wall extending from the axis of the valve to the exhaust outlet, whereby the several stated connections will be established simultaneously when the valve is in intermediate position. 115

In testimony whereof I affix my signature.

FRANK J. SKONIER.
